CLAIM

The ornamental design for a set of elements for office cabins and room dividers, as shown and described.

DESCRIPTION

FIG. 1 is a front perspective view of a set of the elements for building office cabins and room-dividers;
FIG. 2 shows a rear perspective view of FIG. 1;
FIG. 3 shows a perspective view from above of FIG. 1; and,
FIG. 4 shows a different perspective view from below of FIG. 1.
